UNITED STATES PATENT OFFICE.

SHINICHI HIROSAWA, OF SENDAI-SHI, JAPAN.

RECEIVER.

Application filed May 19, 1925, Serial No. 31,390, and in Japan June 3, 1924.

The present invention relates to an electric telephone receiver of the type in which electrical attraction between a conductive body and a semi-conductive body is relied upon to obtain the necessary vibrations and the invention comprises such a receiver having a vibrating arrangement comprising an electrical conductive disc and a semi-electrical conductive disc, these discs being relatively 5 fixed and in intimate contact with each other, the telephonic current being applied directly to the contacting surfaces of both said discs. The term semi-electrical conductive disc is intended to refer to materials 10 such as slate, marble, agate and other like non-hydroscopic materials.

The primary object of the invention is to obtain a sensitive receiver by utilizing the change of attractive force between said discs 20 caused by the passage of telephonic electric current through their contact surfaces, said force being of electrical origin and attributed to so called electroadhesion effect. A further object is to produce a receiver by 25 which the sound and voice can be exactly reproduced. A still further object is to simplify the construction of the receiver and to cheapen the manufacturing cost.

When an electrical current is passed 30 through the contact surface of an electrical conductive disc and a semi-electrical conductive disc which are in intimate contact with each other, an attractive force acts between them, and consequently, if one of said discs is fixed and the other is free, the latter disc will be sensitively vibrated by the 35 change of the current passed through the discs.

This invention has been accomplished by 40 the said principle. By holding an electrical conductive disc and a semi-electrical conductive disc in intimate contact and passing the telephonic current through them, I have been able to construct a sensitive receiver for use 45 in both wire and wireless telephony. Moreover, as this receiver has a high impedance, it is especially convenient for wireless telephony.

The accompanying drawing is a cross sec- 50 tional view of a simply constructed receiver in accordance with the invention.

In the drawing 1 designates the casing; 2 is the ear-piece screwed to the casing and 3 is an aperture at the centre of the said ear- 55 piece, as in the ordinary telephone receiver. The semi-electrical conductive disc 4 is fixed

to a support 6 which is screwed to the base of the casing 1. An electrical conductive disc 5 is placed on the disc 4, and within the ear-piece 2 a washer ring 7 is placed on the peripheral edge of the disc 5, so as to cause intimate contact between the discs. The pressure of this contact may be regulated by screwing the support 6 in or out in order to obtain the most sensitive position. 8 and 81 60 designate lead wires to supply the current to the semi-electrical conductive disc 4 and the conductive disc 5 respectively.

When the telephonic current is supplied to the receiver the change of attractive force 70 between the discs causes the vibration of the disc 5 and hence the sound is reproduced. When the resistance of the disc 4 is exceedingly large or the current is very weak, it is 75 possibly necessary to cover the lower surface of the disc 4 or that surface which is not in contact with the disc 5 with some thin electric conductive material over its whole surface so as to distribute the current uniformly, by which a very sensitive receiver is produced.

Instead of using a single circular disc for the semi-conductive member as illustrated in the drawing, two or more separated disc members may be used. Generally speaking, 80 it is advisable to use thin semi-conductive discs.

Thus, in my present invention, all small amounts of electric energy can be effectively utilized and useless distortions of voice or 85 sound prevented whilst simplifying the construction of the receiver, and reducing remarkably the weight and the cost.

Having now described my invention, and 90 what I claim as new and desired to secure by Letters Patent, is—

1. A receiver of the character described, including relatively vibratory discs arranged in intimate contact with each other, one of which is formed of conductive material and the other of semi-conducting material, and means for supply telephonic current to each of said discs.

2. A receiver as claimed in claim 1, where- 95 in the semi-conductive disc is coated on its non-contacting surface with conducting ma- 100 terial.

In testimony whereof, I have signed my name to this specification at Tokyo, Japan, 105 this 29th day of April, 1925.

SHINICHI HIROSAWA.
